AUTOMATIC WATER REFILLER AND
CUSPIDOR FLUSHERHerman J. Badger and William A. Davis,
Foxburg, Pa.

Application September 2, 1936, Serial No. 99,174

2 Claims. (Cl. 4—262)

This invention appertains to new and useful improvements in appliances for dentist offices and more particularly to an automatic apparatus for maintaining the usual stationary tumbler constantly filled to a certain level and having an overflow serving as the dentist's cuspidor flusher.

The principal object of the present invention is to provide means whereby the usual tumbler from which the dentist obtains water for his mouth syringe may be filled to a definite level and kept at this level without personal attention and wherein the overflow beyond this level is utilized as a flush for the patient's cuspidor.

These and various other important objects and advantages of the invention will become apparent to the reader of the following specification.

In the drawing:—

Figure 1 represents a side elevational view of the apparatus with parts in section.

Figure 2 represents a sectional view taken substantially on the line 2—2 of Figure 1.

Referring to the drawing wherein like numerals designate like parts, it can be seen that numeral 5 represents a tank having a removable cover 6. A water supply line 7 extends to the bottom of this tank 5 and has the shut-off valve 8 therein.

Extending from the bottom of the tank 5 is the conduit 9 which extends to the bottom of the fixed tumbler 10 and from the bottom of the tumbler 10 a connection 11 can be provided for connection to another tumbler and so on to as many as desired in an office.

From the upper portion of the tank 5 a pipe 12 extends downwardly to the perforated circular tube 13 in the patient's cuspidor 14. It can now be seen, that water admitted to the tank 5

will fill the tank to the level 15 and overflow through the pipe 12 to flush the cuspidor 14. Simultaneously water will pass from the tank 5 through the conduit 9 to the tumbler 10, but the water admitted to the tumbler 10 will rise no higher than the level 16 which is the level 15 in the tank 5.

While the foregoing specification sets forth the invention in specific terms, it is to be understood that numerous changes in the shape, size and materials may be resorted to without departing from the spirit and scope of the invention as claimed hereinafter.

Having thus described the invention, what is claimed is:—

1. A dentist appliance comprising a tank having a water inlet at its bottom, a water outlet adjacent its top, a pipe extending from the water outlet, a cuspidor having a perforated spray tube therein connected with the said pipe extending from the water outlet, a water outlet pipe from the bottom of the tank, a stationary tumbler to which the water outlet from the bottom of the tank connects.

2. A dentist appliance comprising a tank having a water inlet supply pipe at its bottom, a water outlet adjacent its top, a pipe extending from the water outlet, a cuspidor having a perforated spray tube therein connected with the said pipe extending from the water outlet, a water outlet pipe from the bottom of the tank, a stationary tumbler to which the water outlet from the bottom of the tank connects, and a valve in the supply pipe to the said tank.
